UNITED STATES PATENT OFFICE

HENRY T. MCANULTY, OF RED LAKE FALLS, MINNESOTA

DRINKING FOUNTAIN

Application filed May 29, 1931. Serial No. 540,904.

My invention has for its object to provide an improved drinking fountain, especially well adapted for use in village and country schools or other places where water under pressure is not ordinarily available; and to this end my invention consists of the novel devices and combinations of devices herein-after described and pointed out in the claim.

My invention in its preferred form is illustrated in the accompanying drawing, wherein like reference notations refer to like parts throughout the several views.

In said drawing Fig. 1 is a front elevation of my improved drinking fountain; Fig. 2 is a vertical section on the line 2—2 of Fig. 1;

Fig. 3 is a top or plan view of the parts shown in Figs. 1 and 2, with the tank cover removed, and

Fig. 4 is detail in perspective showing the relations of the discharge hopper, the elevating bucket and the upright or vertically disposed caging guide of said bucket with the bucket shown in its most elevated position.

The numeral 5 represents any one of four legs disposed at the corners of a rectangle and connected together by suitable braces 6 so as to form a rectangular supporting base for the storage tank 8. The said storage tank 8 is of cylindrical form and the supporting base is provided with a circular band 7 rigidly secured to the upper ends of the legs 5 and of slightly larger diameter than the tank 8, thereby permitting the lower end of the tank 8 to telescope within the band 7 and rest on inturned flanges of the feet 5 of the supporting base. The tank 8 is therefore readily removable from the supporting base whenever desired. The tank is provided with a removable cover 9. The numeral 10 represents a supporting bracket fixed to one pair of the legs 5 and projecting outward therefrom into proper position for supporting a fountain bowl 11 as clearly shown in Figs. 1 and 2 of the drawing. The numeral 12 represents a discharge hopper located within the tank 8 with its upper end located only a short distance below the upper end of the tank and having its lower end connected by a pipe 13 to the fountain bowl 11,

as clearly shown in Fig. 2 of the drawing. The numeral 14 represents a bucket-loading well which extends below the main or body portion of the bottom of the tank 8 and is shown as of rectangular form in cross section of the proper size to receive the water elevating valved bucket 15. The numeral 16 represents a caging guide for the said water bucket 15, which guide is disposed in an upright or vertical position and extends on three sides above the top of the discharge hopper 12 and has one of its walls abutting the inner wall of said discharge hopper 12. The bucket 15 is cut away on that side thereof facing the hopper 12 to afford an outflow opening 15a for the water when the bucket is in its uppermost position, as clearly shown in Fig. 4 of the drawing; and that particular side of the caging guide 16 directly abutting the hopper 12 is cut away in that part thereof which projects above the hopper 12 to afford a passage 16a for the water coming from the bucket through the side opening 15a thereof and thus allowing the water from the bucket to discharge into the top of the hopper 12. 75

The numeral 17 represents a bell crank shaped spider bracket the long arm of which is formed of a tube, the outer end of which extends through and is secured to the wall of the tank 8. The short arm of the spider 80 17 has a bifurcated foot which abuts and rests on the upper end of the outer wall of the caging guide 16, as best shown in Fig. 2 of the drawing. The said spider 17 has a little pulley or sheave 18 at its elbow over 85 which passes a suitable flexible connection such as a light cable or strong cord 19 the lower end of which is attached to the bail of the bucket 15, as clearly shown in Figs. 2 and 4 of the drawing. The upper end of this 90 connection 19 passes through the tubular arm of the spider 17 and thence over another guide pulley 20 supported by bracket 21 fixed to the tank 8, as shown in Fig. 2 of the drawing. The projecting end of said connection 95 19 is provided with a handle 22, by which the operator can raise the loaded bucket from its filling position to its discharging position at will.

The upright caging guide 16 for the bucket 100

15 has two of its walls cut away to afford openings 16b which are in constant communication with the water within the tank 8 when the device is in working condition. The 5 bucket 15 has in its bottom a check valve 15b.

The lower end of the delivery pipe 13 of the hopper 12 is curved and its outer end projects into the fountain bowl 11 so that the 10 water will be delivered in a jet and the rim of the bowl 11 at the back of the bowl is extended upward and inward on a curved line as a guard to prevent the person using the 15 fountain from getting his head too low in the bowl.

The construction and disposition of the parts being as above described, the operation is probably obvious from the above stated 20 specifications. However, the operation may 25 be briefly summarized as follows:

Assuming the tank 8 to have been filled to the desired extent, with drinking water, the elevating bucket will stand in its lowermost 30 position under the action of gravity, as shown 35 in Fig. 2 of the drawing. In this position the bucket will be loaded with water and whenever any person desires to have a drink, all he needs to do is to take hold of the handle 22 of the flexible connection 19 and pull 40 downward thereon until the bucket is drawn upward to its limit or into the position shown 45 in Fig. 4 of the drawing. As soon as this occurs the water will flow out of the bucket into the mouth or open upper end of the hopper 12 and the body of this hopper is at such 50 an elevation above the fountain bowl 11 that the pressure under the action of gravity on the water within the hopper 12 and pipe 13 will be sufficient to discharge the water in 55 a jet from the lower end of said pipe 13 at the fountain bowl 11, where it can be readily 60 reached by the person desiring the drink of water. It should be carefully noted that the discharge of the water from the elevating 65 bucket into the hopper 12 is secured without any tilting action of the bucket. The bucket simply has a straight up and down sliding motion, and this is the radical feature of my 70 improvement over the prior art. In all prior 75 devices for a similar purpose so far as known to me the bucket has always been given a tilting action to bring it into discharging position. This has added complications in structure with greatly increased wear and tear on 80 the parts, or otherwise stated, my improvement has effected a great simplification in the structure thereby reducing the first cost of the device and increasing the endurance of 85 the device.

60 Attention is called to the fact that all the

parts located within the tank 8 are readily detachable from each other and removable from the said tank. For example, the discharge pipe 13 of the hopper 12 is made in two sections adapted to be united by a union 13a and therefore separable at will. The spider 17 is clamped to the wall of the tank 8 by nuts 17a and 17b and therefore can be readily removed. The caging guide 16 is provided at its upper end with the hook 16c, which is adapted for engagement with the upper edge of the hopper 12, and at its lower end is slidably engaged with the interior surface of the loading well 14, and, therefore, 90 can be readily lifted out of the tank. When the caging guide has been removed, access may be had to the lower portion of the interior of the tank for opening the union 13a. The hopper 12 is provided with an offset 95 tongue 12a adapted to engage with a cross bar 12b soldered to the wall of the tank 8, and therefore the hopper can be readily lifted out from the tank when the union between the sections of the pipe 13 has been opened up. 100

It should be further noted that in practice the tank 8 and all the parts located therein are made of some non-corrosive metal. The same remark applies to the fountain bowl. The device is therefore an extremely sanitary 105 one for the use intended.

It will of course be understood that more or less of the details could be changed without departing from the spirit of my invention herein disclosed and claimed.

What I claim is:

In a liquid dispenser, the combination with a storage tank and an outside discharge means, of a hopper, the outlet of said hopper being connected to said outside discharge means, a non-tilting elevating bucket having a free opening in one side thereof, a vertically disposed caging guide for said bucket located within said tank adjacent to said hopper, one side of said caging guide being imperforate and extending to the upper edge of said hopper, the remaining three sides of said caging guide extending above the upper edge of said hopper, the open side of said bucket facing the imperforate side of said caging 110 guide and disposed in such proximity to said imperforate side that the imperforate side of said caging guide forms a closure for the open side of said bucket at all times except when said bucket is raised to its extreme uppermost position above said imperforate side, and hand operating means for elevating said bucket.

In testimony whereof I affix my signature.

HENRY T. McANULTY.
